US0D1046649S

(12) **United States Design Patent** (10) **Patent No.:** **US D1,046,649 S**
(45) **Date of Patent:** **** Oct. 15, 2024**

(54) **PET LOCATOR**

(71) Applicant: **Shenzhen Omni Intelligent Technology Co., Ltd.**, Shenzhen (CN)

(72) Inventor: **Chunyan Lai**, Shenzhen (CN)

(73) Assignee: **Shenzhen Omni Intelligent Technology Co., Ltd.**, Shenzhen (CN)

(**) Term: **15 Years**

(21) Appl. No.: **29/860,887**

(22) Filed: **Nov. 23, 2022**

(51) LOC (14) Cl. **30-04**

(52) U.S. Cl.

USPC **D30/152**; D30/199; D10/70; D10/104.1
